Inventor:
M. C. Crouk

UNITED STATES PATENT OFFICE,

M. C. CRONK, OF AUBURN, NEW YORK.

CHURN.

Specification of Letters Patent No. 33,030, dated August 13, 1861.

To all whom it may concern:

Be it known that I, M. C. CRONK, of Auburn, in the county of Cayuga and State of New York, have invented certain new and useful Improvements in Churns; and I do hereby declare that the following is a full, clear, and exact description of the same, reference being had to the accompanying drawings, and to the letters of reference 10 marked thereon, in which—

Figure 1 is a vertical section and Fig. 2 a side elevation.

The nature of my invention consists in the employment and arrangement of certain devices the peculiarities of which will be hereinafter fully set forth.

To enable others skilled in the art to make and use my invention I will now describe its construction and operation.

(A) represents a vessel of suitable dimensions provided near its top with the sheath (y) the object of which will be more fully appreciated hereafter.

(B) represents an adjustable frame.

(d d) are two revolving dasher staves, each of which is provided with the cog wheels (h and h').

(C) represents the main or center dasher staff, which extends some distance above the 30 top of the churn, as fully shown in the drawings.

(I) represents a cog wheel on staff (C), and by means of which cog wheels (h h') are operated. The lower end of staff (C) is 35 stepped, between which step and the bottom of frame (B) is the spiral spring (m).

(e) represents a circular plate which revolves with the main dasher staff.

(b) is a cross piece on frame (B). In the 40 center of said cross piece (b) is likewise a circular plate of the same dimensions as plate (e). The rubbing surfaces of each of these plates should be ridged something like the ordinary mill stone, the advantage of 45 which will be more fully seen hereafter.

(a) represents a stationary funnel which surrounds main staff (C) just above the plate formed on the cross piece (b).

(x x x) are dasher boards, so arranged on 50 the three dasher staves that the boards on staves (d d) will revolve in the spaces between the boards on main staff (C) and vice-versa.

(G) represents an upright, shaped as shown in Fig. 2. Said upright is supported 55 by means of sheath (y), and may be easily taken off and again adjusted in place whenever necessary.

(o) represents a shaft, which extends 60 through the upright (G).

(D) is the driving wheel on the end of shaft (o), and which is operated by means of crank (p).

(g) represents a small cog wheel on the 65 end of staff (C), which works into the driving cog wheel (D).

(c) represents a thumb screw which passes vertically through the upright (G), into the end of main staff (C).

(K) represents an adjustable funnel for 70 the purpose of conveying the milk to the mouth of the stationary funnel (a).

The operation of my machine is as follows. The frame (B) and top (F), being properly adjusted, motion is given to the 75 dasher staves by means of crank (p). While the machine is in motion the milk is poured in funnel (K) which conveys it to funnel (a), from thence it descends between the circular plates, which are kept closely pressed 80 together by spiral springs (m), thus grinding as it were the globules of the milk. As it falls from the circular plates the dasher boards by their contrary and rapid revolutions complete in a very short time the operation. 95

What I claim and desire to secure by Letters Patent is—

1. The employment of spiral spring (m) 90 in combination with main dasher staff (C) and circular plate (e), when all shall be operated in the manner and for the purpose specified.

2. The revolving dasher staves (C) and (d d), frame (B), funnel (a) circular plate 95 (e), and spiral spring (m) when all shall be arranged in the manner and for the purpose herein set forth and described.

In witness that I claim the foregoing I have hereunto set my hand in the presence 100 of witnesses.

M. C. CRONK.
